UNITED STATES PATENT OFFICE.

EDWARD J. WORCESTER, OF WORCESTER, MASSACHUSETTS, ASSIGNOR TO
GEORGE BURNHAM AND ASA GODDARD, OF SAME PLACE.

DRILL-GRINDING ATTACHMENT FOR DRILLING-MACHINES.

SPECIFICATION forming part of Letters Patent No. 325,373, dated September 1, 1885.

Application filed January 30, 1884. (No model.)

To all whom it may concern:

Be it known that I, EDWARD J. WORCESTER, a citizen of the United States, residing at Worcester, in the county of Worcester and State of Massachusetts, have invented a new and useful Improvement in Drill-Grinding Attachments for Drilling-Machines, of which the following is a specification, with accompanying drawings, illustrating my invention, and in which—

Figure 1 shows a front elevation of a drilling-machine with my drill-grinding apparatus attached thereto. Fig. 2 is a side elevation of the same. Fig. 3 shows a top view of the grinding device; and Fig 4 is a detached and side view of the same with the drill-rest J removed.

Similar letters refer to similar parts in the several views.

The object of my invention is to provide a grinding apparatus so attached to a drilling-machine as ordinarily used by blacksmiths and others, and suitably connected therewith, that the rotation of the balance-wheel of the drilling-machine will operate the grinding apparatus and enable workmen to resharpen their drills as required.

In Fig. 1, A indicates a portion of the framework of the drilling-machine; B, the crank; C, the balance-wheel shaft driven by the gearing *a b c*, suitably held by the frame-work of the machine in the manner well known, and common to drilling-machines of this class. D is the balance-wheel, and E the drill-spindle, all arranged and operating in the usual and well-known manner in this class of drilling-machines.

To the frame A is attached the plate F, having the lugs *f f*, which furnish bearings for the pintles *g*, by which the swinging plate G is hinged to the plate F. The swinging plate G has at its top edge the bearings *d d*, for the revolving arbor H, carrying the grinding-wheel H'. A thumb-screw, *e*, passes through the plate G and rests against the plate F, and a spring, *s*, Fig. 4, is placed between the plates F and G, and below the hinge, pressing the two plates apart.

Upon the arbor H is a friction-wheel, K, revolving in the same plane with the balance-wheel D, and which may be brought against the edge of the balance-wheel by means of the thumb screw *e*, acting against the plate F, and the motion of the balance-wheel D thereby communicated to the arbor H and the grinding-wheel H'. By retracting the screw *e* the spring *s*, in a state of compression, will draw the plate G, with the arbor H and friction-wheel K, away from the balance-wheel D, thereby destroying the contact between the balance-wheel and the friction-wheel K.

To the plate F, I attach the drill-rest J, arranged at an angle to the plane of rotation of the grinding-wheel H', so as to hold the drill in the proper position to present its cutting-edges to the face of the grinding-wheel and allow the same to be accurately ground.

What I claim as my invention, and desire to secure by Letters Patent, is—

1. The combination, with the balance-wheel of a drilling-machine, of a grinding apparatus consisting of the arbor H, carrying a grinding-wheel and the friction-wheel K, swinging frame or plate G, holding the arbor H, screw *e*, and spring suitably attached to the plate G, so as to act against the screw *e*, all arranged as described, and for the purpose set forth.

2. The combination, with the balance-wheel of a drilling-machine, of a drill-grinding apparatus consisting of swinging frame G, arbor H, carrying a grinding-wheel and a friction-wheel, having means, substantially as described, for bringing said friction-wheel into contact with the balance-wheel, and a stationary drill-rest attached to the frame of the machine, formed of an angle-iron set obliquely to the grinding-wheel, all combined and operating as described, and for the purpose set forth.

EDWARD J. WORCESTER.
